UNITED STATES PATENT OFFICE.

AUGUSTUS SEAVER, OF BOSTON, ASSIGNOR OF ONE-THIRD TO CHARLES CURTIS, OF NEWTON, MASSACHUSETTS.

BOOT OR SHOE.

SPECIFICATION forming part of Letters Patent No. 314,302, dated March 24, 1885.

Application filed January 19, 1885. (No model.)

To all whom it may concern:

Be it known that I, AUGUSTUS SEAVER, of Boston, in the county of Suffolk and State of Massachusetts, have invented certain Improvements in Boots and Shoes, of which the 5 following is a specification.

This invention has for its object to provide certain improvements in boots and shoes whereby the metallic fastenings used in securing the upper to the inner sole in lasting are prevented from projecting above the inner surface of said sole; and it consists in a boot or shoe having its inner sole channelled on its outer surface to form an inwardly-projecting 15 flap, and the upper secured to said flap only by the lasting-tacks or other metallic fastenings used in lasting, the peculiar form of the flap enabling it to be raised to allow a metallic clinching-plate to be inserted under it for 20 the purpose of turning the points of the lasting-tacks, while the location of the flap on the outer surface of the inner sole enables the clinching-plates to be easily removed, all of which I will now proceed to describe.

25 Of the accompanying drawings, forming a part of this specification, Figure 1 represents a view of the outer surface of the inner sole. Fig. 2 represents a section on line $\alpha\alpha$, Fig. 1. Fig. 3 represents a transverse section of the 30 completed boot or shoe.

The same letters of reference indicate the same parts in all the figures.

In the drawings, a represents the upper and b the inner sole.

35 In carrying out my invention I channel the outer surface of the inner sole to form a flap, c , the attached portion of which is near the edge of the sole, so that the free edge extends inwardly toward the center of the sole. This 40 form of the flap and its location on the outer surface of the inner sole enable it to be raised to receive metallic clinching-plates ff , to be used for clinching the lasting-tacks t or other metallic fastenings.

I am aware that an inner sole has been channelled on its inner surface to receive clinching-plates which turn the points of the lasting-tacks and prevent them from passing above the inner surface of the inner sole. 45

I am also aware that an inner sole has been 50 channelled to form an inwardly-projecting flap.

My invention is therefore confined to a boot or shoe having the outer surface of the inner sole channelled to form a flap which projects 55 inwardly from the edge of the sole, and the upper secured to said flap only by tacks or other metallic fastenings clinched between the flap and the body of the inner sole. The arrangement of the flap enables the clinching- 60 plates to be more easily removed from the flap than when the latter is formed on the inner surface of the sole. The plates can also be removed directly after using, so that the necessity of removing the boot or shoe from the 65 last is avoided. It will not be necessary, therefore, to provide a large number of clinching-plates, as the plates do not have to remain in the sole until the boot or shoe is removed from the last, as is the case when the flap is 70 formed on the inner surface.

I claim—

A boot or shoe having an inwardly-projecting flap on the outer surface of the inner sole, and the upper secured to said flap only by 75 metallic fastenings passed through the edge of the upper and the flap, and clinched between the flap and the main portion of the inner sole, as set forth.

In testimony whereof I have signed my 80 name to this specification, in the presence of two subscribing witnesses, this 10th day of January, 1885.

AUGUSTUS SEAVER.
